(No Model.)

R. M. HUNTER.
ELECTRIC RAILWAY CAR.

No. 424,206.

Patented Mar. 25, 1890.

Attest:
Larry Drury
S.M. Purcell

Inventor:

R. M. Hunter

UNITED STATES PATENT OFFICE.

RUDOLPH M. HUNTER, OF PHILADELPHIA, PENNSYLVANIA.

ELECTRIC-RAILWAY CAR.

SPECIFICATION forming part of Letters Patent No. 424,206, dated March 25, 1890.

Original application filed September 23, 1886, Serial No. 214,309. Divided and another application filed June 1, 1887, Serial No. 239,930. Again divided and this application filed February 18, 1888. Serial No. 264,456. (No model.)

To all whom it may concern:

Be it known that I, RUDOLPH M. HUNTER, of the city and county of Philadelphia, and State of Pennsylvania, have invented an Improvement in Electric-Railway Cars, of which the following is a specification.

The claims of this application correspond to claims 56, 57, 59, 62, 63, 64, 65, 66, 67, and 68 of my application Serial No. 239,930, and 10 have been erased from that case.

My invention has reference to electric rail-ways; and it consists in certain improve-ments, all of which are fully set forth in the 15 following specification, and shown in the accompanying drawings, which form part thereof.

This application is a division of my applica-tion, Serial No. 239,930, filed June 1, 1887, 20 which was a division of my earlier applica-tion, Serial No. 214,309, filed September 23, 1886.

The object of my invention is to provide a suitable construction of motor-connection with the axles. I provide one or more motors 25 with a common shaft having worm-wheels on each end to mesh with worms on two different axles. I prefer to arrange the motor-shaft oblique, so that one worm is above one axle and the other worm below the other axle.

30 My invention also comprehends certain im-provements in the connections of the motors with the source of power to provide proper regulation.

In the drawing is shown a sectional eleva-tion of an electric-railway car embodying my 35 invention.

B B' are the supply or working conductors to supply current to the motor-circuit E. C is the car.

40 D is a motor-frame, preferably supported upon the car-axles d or their boxes, the car-body being in most cases supported on springs. To this frame D one or more electric motors D² are secured, all preferably having the same 45 shaft or armature-shaft, which is also prefer-ably set on an incline. Carried upon the ends of this shaft are the worms D⁴, which mesh with worm-wheels D' on the axles d of the car, one of these worms being above one worm-50 wheel and the other below the other worm-

wheel. The obliquity of the armature or motor shaft is not necessary, though desirable.

E is the motor-circuit supplying current from the collectors to the motors. To enable the proper governing of all the motors most 55 perfectly I connect all of the armatures of the different motors, be they on one car or on one train, in one circuit E², and all of the field-magnets in another circuit E', each provided with a current-indicator e. The armature-circuit E² has a resistance-changer e³ and cur-rent-reverser E³, while the field-magnet cir-cuit E' has its own resistance-changer e' and current-reverser E⁴. By this means the arma-ture-circuit may be regulated, cut out, or have 60 its current reversed without affecting the field, and vice versa.

The construction of the motors shown in Fig. 2 is similar to that set out in my applica-tion, Serial No. 200,400, filed April 28, 1886, on 70 which the armature is stationary and the field-magnets revolve. The directions of the cur-rents are indicated by the arrows.

In this application I do not limit myself to the mere details shown, as they may be varied 75 in many ways without departing from the invention herein set out.

Having now described my invention, what I 80 claim as new, and desire to secure by Letters Patent, is—

1. In an electrically-propelled vehicle, the combination of the two axles, with a worm-wheel on each axle, an electric motor having its shaft extending from axle to axle, and a worm on each end meshing with the worm-wheels to drive both axles simultaneously.

2. In an electrically-propelled vehicle, the combination of the two axles, with a worm-wheel on each axle, an electric motor arranged obliquely and having its shaft extending from 90 axle to axle, above one axle and below the other, and a worm on each end meshing with the worm-wheels to drive both axles simultaneously.

3. In an electrically-propelled vehicle, the 95 combination of the two axles, with a worm-wheel on each axle, an electric motor arranged obliquely and having its shaft extending from axle to axle, above one axle and below the other, a worm on each end meshing with the 100

worm-wheels to drive both axles simultaneously, and a motor-frame for supporting the motor carried by the axles.

4. In an electrically-propelled vehicle, the combination of two axles, an electric motor having its shafting extending from axle to axle, a worm operated by each end of the shaft and meshing with the worm-wheels to drive both axles simultaneously, and a frame-work connected to the axles for holding the worms at a fixed distance from the axles.

5. In an electrically-propelled vehicle, the combination of two axles, a worm-wheel on each axle, a main frame connecting the two axles, a motor supported upon said main frame and having its shaft arranged obliquely, a worm-wheel arranged above said axle, and a second worm-wheel arranged below the other axle and each operated by the same shaft, a frame extending from said main frame upwardly to support and hold one of the worms in contact with the upper part of one of the worm-wheels, and a second frame extending downward and supporting the other worm-wheel in contact with the end portion of the other worm-wheel.

6. In an electrically-propelled vehicle, the combination of an axle, a worm-wheel upon said axle, a frame supported upon said axle, a motor secured to said frame and having its shaft arranged obliquely, a worm-wheel arranged obliquely and operated by said oblique shaft of the motor, and framing carried by the aforesaid frame to hold the worm in a fixed relation with respect to the worm-wheel and axle.

7. In an electrically-propelled vehicle, the combination of two axles, a main frame supported by said axles, a worm-wheel upon one of the axles, a motor carried by the main framing having its shaft arranged obliquely, a worm arranged obliquely and adapted to be rotated by said oblique shaft, and framing for holding said worm to the worm-wheel.

In testimony of which invention I hereunto set my hand.

RUDOLPH M. HUNTER.
